JAR DEVICE

Albert S. Baptie, Bakersfield, Calif., assignor to
 Shell Development Company, San Francisco,
 Calif., a corporation of Delaware

Application March 22, 1937, Serial No. 132,293

5 Claims. (Cl. 255—27)

This invention pertains to a jarring tool for use in connection with devices or instruments lowered into boreholes and operated therein by means of electrical current.

- 5 In various drilling operations, use is made of devices such as logging instruments, thermometric instruments, cement vibrators, casing gun perforators, fishing magnets, etc., which employ or are operated by electrical current.
- 10 These tools or instruments may be lowered into a well at the end of a drill string, tubing string, or sucker rod string, although they are most commonly supported by a flexible cable made of wire, wire and rubber, fabric, hemp, etc., comprising 15 an insulated electrical conductor.

It frequently happens that these devices become stuck or jammed in the borehole, and that attempts to disengage them by exerting a pull on the cable cause the latter to break. Long and 20 costly fishing operations must then be resorted to in order to retrieve the instrument, and if they fail the instrument may become entirely lost in the hole.

It is the object of this invention to provide a 25 jarring or knocking tool for electrical devices whereby said devices could be released from engagement with obstructions within boreholes without the necessity of exerting an excessive pull on the supporting cable.

30 It is a further object of this invention to provide a jar which would permit electric current to be supplied to said electrical devices during the time when the jar is operated.

It is another object of this invention to provide 35 a jar constructed so that the electrical conductor passing therethrough is not subjected to any appreciable tension or compression stresses during the operation of the jar.

These and other objects and features of the 40 invention will appear more clearly from the following description taken with reference to the attached drawing in which

Fig. 1 is an elevation view, partly in cross section, of a jar forming one embodiment of the 45 present invention.

Fig. 2 is a transverse cross-sectional view taken along line A—A of Fig. 1.

Fig. 3 is a cross-sectional elevation view of a 50 jar forming another embodiment of the present invention.

Fig. 4 is a transverse cross-sectional view taken along line B—B of Fig. 2.

Referring to Fig. 1, an electrical conductor 1 55 is shown within the strands of a cable 2 supporting the jar and any electrically operated de-

vice attached thereto. A cable socket 5 provided with an axial bore is affixed to the end of the cable 2 by introducing the end of the cable into said bore and clamping it there by a suitable means, for example a molten friction metal such as babbitt, as shown at 4. The cable socket 5 may be provided with external serrations, shown at 3, to facilitate fishing in case the jar should fail to operate effectively. The lower end of the axial bore through the socket 5 is provided 10 with screw threads 6, holding an inner jar member, comprising a jar mandrel 7, provided with an axial bore for the electrical conductor and with a thickened lower end, forming, for example, a T-shaped jar head as shown at 10. The jar 15 mandrel is adapted to move slidingly through an axial bore 8 in the upper part of an outer jar member or jar body 9. The jar body is an elongated metallic bar of generally cylindrical shape having a longitudinal slot 12 through its 20 middle portion, the jar head 10 being adapted to move axially within said slot. The inner and the outer jar members are capable of telescopic motion with regard to each other, the mandrel 7 sliding through the bore 8, and the jar head 10 25 moving within the slot 12. The extent of this motion is limited in one direction by the abutment of the lower face of socket 5 against the upper face of the jar body 9, and in the other direction by the abutment of jar head 10 against the upper end of the longitudinal slot 12. The conductor 1 passes through the axial bore of the jar mandrel and the jar head, and is housed, 30 below the lower face of the jar head within a flexible sheath or shielded conduit 11, which is 35 affixed between said lower face of the jar head and the lower end of slot 12. This sheath may consist, for example, of a length of a coiled resilient tubing, or may be formed by a thin metallic wire tightly wrapped around the insulated 40 conductor. The length of the shielded conductor coiled below the jar head is selected in such a manner that it is not fully expanded even at the moment when the jar head abuts the upper end of the slot 12 at the end of its upward stroke, 45 so that the conductor is never subjected to tension stress. On the other hand, the length of the jar mandrel and of the slot 12 is selected in such a manner as to provide an adequate space to house the compressed coiled conductor when the 50 lower face of socket 5 abuts the upper face of the jar body 9 at the end of the downward stroke of inner member, so that the conductor cannot be crushed between the jar head and the lower end of slot 12. The purpose of the resilient spiral 55

sheath housing the conductor is to protect it from contact with the mudflush or with any other corrosive or abrasive substances within the borehole, and to insure an orderly and uniform coiling of said conductor within the slot 12 during the telescoping motion of the jar.

The lower end of the jar body 9 has an axial bore providing a passage for the electrical conductor, which may be suitably clamped therein 10 to prevent wear due to friction. Any suitable means, such as a tapped box 13 at the lower end of the jar body may be used to attach the jar to any desired electrical device, such as surveying, logging, orienting thermometric and water locating instruments, gun perforators, cement vibrators, fishing magnets, etc.

Fig. 4 shows a somewhat different embodiment of the present invention, wherein the outer jar members or jar body comprises a hollow cylinder 9B, closed at both ends by suitable heads. For example, the upper end may be closed by a screw-threaded plug 9A, provided with an axial bore forming a passage for the mandrel of the inner member. The coiled conductor is housed 20 below the jar head 10 in a closed chamber 12 formed within said hollow cylinder between the jar head 10 and the lower head 9C of the jar body and is effectively protected against injury by outside bodies. The protective sheath 11 around the coiled conductor may therefore be omitted, if desired. However, its use has also been found advantageous with this type of jar, 25 since it insures a uniform coiling of the conductor and prevents breaks due to irregular coiling and creasing. A spiral or helical sheath, snugly fitting within the walls of the chamber 30 35 12 may be conveniently used in this case.

In operation, the jar mechanism is attached to a desired electrical device and is lowered there- 40 with into the well at the end of a cable comprising an insulated electrical conductor. If desired, the jar may be lowered into the well at the end of a piping or tubing string, or at the end of a sucker rod string, the insulated conductor being run inside the tubing string or alongside the sucker rod string. The socket 5 is provided in such cases with suitable attaching means connecting it to the tubing, piping or rod string.

The jar is lowered into the bore hole and main- 50 tained therein either in its extended position or in a contracted (or closed) position during the operation of the electrical device. If it is in its extended position, it is free to operate telescopically at any time that the jar body or the instrument affixed to the jar body becomes lodged 55 or stuck in the bore hole. If it is in a contracted (or closed) position, that is, with the upper face of the jar body abutting the lower face of the cable socket, the jar is maintained in this position by means of a frangible shear pin or pins 10A holding the inner and outer jar members in fixed 60 relationship to each other, as shown in Fig. 2.

If the apparatus becomes stuck or jammed in the bore hole, a sufficient pull is exerted on the 65 cable to break the shear-pin, whereupon the cable socket 5 is raised with the cable, causing the jar mandrel to slide through the axial bore in the jar body, until a sharp blow is struck by the jar head against the upper end of the slot 12 (Fig. 1) or against the plug 9A (Fig. 2). This procedure may be repeated several times until the apparatus is sufficiently freed from the ob- 70 struction to allow it to be raised without danger of cable rupture.

75 It will be seen that a jar constructed according

to the present invention allows electric current to be supplied at all times to the electrical device attached to the jar. For example, if the jar is used with a fishing magnet, used to retrieve tools lost in the hole, it is essential that electric current be supplied to the magnet during the time the jar is operated, since any interruption of the current would cause the magnet to release its load and result in the failure of the whole operation. Likewise, if the jar is used with a cement 10 vibrator such, for example, as described in the co-pending application, Ser. No. 117,914, filed December 28, 1936, by Clarence R. Dale, it is im- 15 portant that the vibrator and the jar be capable of operating simultaneously, since the vibrating 15 action of the vibrator cooperates with the jarring action of the jar in disengaging the apparatus from the obstruction.

It is understood that the jar mechanism forming the subject matter of the present invention is 20 in no way limited to the embodiments described above, but is capable of various modifications coming within the scope of the appended claims. For example, it is obvious that the inner member may be attached to the electrical device, and the 25 outer member to the cable. In particular it should be pointed out that the force of the blows delivered by the jar can be controlled by properly varying the length of the jar mandrel and the 30 weight of the two relatively movable parts of the jar mechanism. The latter object may be achieved, for example, by attaching sinker bars or suitable subs provided with axial bores for passing the electrical conductor either to the cable 35 socket or to the jar body in a manner understood by those versed in the art.

I claim as my invention:

1. In a jar for an electric device lowered into a borehole, supporting means for the jar, an elongated inner jar member, an elongated longitudinally recessed outer jar member, one of said members being attached to the supporting means and the other to the electric device, said members being linked for limited axial telescopic motion with regard to each other, a bore through each member, an insulated conductor associated with the supporting means and passing through the bore in the members to the electric device, said conductor having a coiled section housed within the recessed jar member, said coiled section being of sufficient length to permit a full telescopic stroke of the jar members with regard to each other.

2. In a jar for an electric device lowered into a borehole, supporting means for the jar, an elongated inner jar member, an elongated longitudinally recessed outer jar member, one of said members being attached to the supporting means and the other to the electric device, said members being linked for limited axial telescopic motion with regard to each other, an axial bore through each member, an insulated conductor associated with the supporting means and passing through the axial bore in the members to the electric device, said conductor having a coiled section housed within the recessed jar member, said coiled section being of sufficient length to permit a full telescopic stroke of the jar members with regard to each other, and a pin holding the two members in fixed relationship to each other.

3. In a jar for an electric device lowered into a borehole, supporting means for the jar, an elongated inner jar member, an elongated longitudinally recessed outer jar member, one of said members being attached to the supporting means

means and the other to the electric device, said members being linked for limited axial telescopic motion with regard to each other, an axial bore through each member, an insulated conductor associated with the supporting means and passing through the axial bore in the members to the electric device, said conductor having a coiled section housed in a resilient helical sheath within the recessed jar member, said coiled section being of sufficient length to permit a full telescopic stroke of the jar members with regard to each other.

4. In a jar for an electric device lowered into a borehole, supporting means for the jar, an elongated tubular inner member attached to said supporting means, said member having a thickened lower portion, an elongated solid outer jar member attached to the electric device, means linking said members for limited telescopic motion with regard to each other comprising an axial bore in the upper portion of the solid outer member adapted to fit slidably around the inner member, a longitudinal slot through the middle portion of the solid outer member, said slot having a width at least equal to the diameter of said bore, the thickened lower portion of the inner member being adapted to move axially within the upper portion of said slot, an axial bore through the lower portion of the outer member, an insulated conductor associated with the supporting means and passing through the tubular inner member and through the slot and the lower

bore in the outer member to the electric device, said conductor having a coiled section housed in a resilient helical sheath within the lower portion of slot in the outer member below the thickened portion of the inner member, said coiled section being of sufficient length to permit a full telescopic stroke of the jar members with regard to each other.

5. In a jar for an electric device lowered into a borehole, supporting means for the jar, an elongated inner tubular jar member attached to the supporting means, said member having a thickened lower portion, an elongated outer tubular jar member, a head closing said member at each end, means linking said members for limited telescopic motion with regard to each other comprising an axial bore through the upper head of the outer member adapted to fit slidably around the inner member, a chamber below said head, the thickened portion of the inner member being adapted to move axially within the upper portion of said chamber, an axial bore through the lower head of the outer member, an insulated conductor associated with the supporting means and passing through the tubular members to the electric device, said conductor having a coiled section housed within the lower portion of the chamber in the outer member below the thickened portion of the inner member, said coiled section being of sufficient length to permit a full telescopic stroke of the jar members with regard to each other.

ALBERT S. BAPTIE.
